UNITED STATES PATENT OFFICE.

HARRIET LAVINIA FRASER, OF NEW YORK, N. Y.

SNOW-PLOW.

SPECIFICATION forming part of Letters Patent No. 394,350, dated December 11, 1888.

Application filed May 4, 1888. Serial No. 272,812. (No model.)

To all whom it may concern:

Be it known that I, HARRIET LAVINIA FRASER, of the city, county, and State of New York, have invented a new and Improved 5 Snow-Plow, of which the following is a full, clear, and exact description.

The object of the invention is to provide a new and improved snow-plow, which is simple and durable in construction and very effectively removes the snow from railroad-tracks.

The invention consists of certain parts and details and combinations of the same, as will be fully described hereinafter, and then 15 pointed out in the claims.

Reference is to be had to the accompanying drawings, forming a part of this specification, in which similar letters of reference indicate corresponding parts in all the figures.

20 Figure 1 is a longitudinal sectional elevation of the improvement as applied. Fig. 2 is a perspective view of the middle section of the snow-plow, parts being broken out. Fig. 3 is an end elevation of the improvement, and 25 Fig. 4 is a perspective view of a detail.

The improved snow-plow A is provided with a vertical frame, B, on which are pivoted the rods C and C', each having at its end a hook, C², adapted to pass into a bearing, D', secured 30 in front of the locomotive D, which serves to push the snow-plow into the snow drift or bank on the railroad-track. On the lower end of the frame B are mounted to rotate the wheels E, traveling on the track-rails, and 35 from the front of the said frame B project the rods E', on which are mounted the wheels E², held in front of the wheels E, and also adapted to travel on the track-rails.

The frame B supports at its front the three 40 plow-sections F, G, and H, located one above the other and one in front of the other, as is plainly shown in Fig. 1. The lower section, F, is pivotally connected with the frame B and is supported on the axle of the front 45 wheels, E². The middle section, G, is pivotally connected with the lower section, F, by rods or stays I, and the upper section, H, is similarly connected with the middle section, G, by rods or stays J. The middle and upper 50 sections, G and H, are also pivotally connected with the horizontal rods K K', respectively, each provided at its inner end with the two

prongs K² and K³, extending in opposite directions, and of which the upper prong, K², is adapted to rest against the frame B, while the 55 lower prong, K³, is curved and held in a socket, K⁴, secured to the side of the frame B. This socket K⁴ is shaped similarly to the prong K³ and permits a swinging motion of the respective rod, K or K'.

Instead of making the socket K⁴ as shown in Fig. 1 it may be formed as shown in Fig. 4, in which it consists of the bracket K⁵, secured to the frame B, and of the curved arm K⁶, pivoted on the said bracket K⁵. The curved arm 65 K⁶ corresponds in shape with the prong K³ and turns with the latter when the rod K or K' swings up or down. The upward movement of the said rods K or K' is limited, however, by the prong K² resting against the frame B, as 70 shown in Fig. 1.

The upper section, H, is connected near its rear end with the chains L, from which extend the branch chains L', connected with the middle section, G. The chains L run upward 75 and pass over the pulleys L², mounted in the upper end of a frame, N, mounted to slide vertically in the bearings B' and B², formed on the frame B. Bolts N' are secured to the frame B and project through vertical slots N³, 80 formed in the said frame N, and nuts N² screw on the outer ends of the said bolts N' and against the said frame N, so as to fasten the latter to the vertical frame B at any desired place. The chains L pass downward from the 85 pulleys L² and are wound upon the drum O' of a windlass O, held on the inside of the frame B, being of any approved construction. By operating the windlass O the chains L are wound upon and unwound from the said drum 90 O', and the plow-sections H and G are raised or lowered correspondingly.

Each plow-section F, G, or H consists, principally, of two parts united in their middle by bolts or other suitable means, as shown in 95 Fig. 2. Each section consists of the lower flanges, F', G', or H', which continue into the rearwardly and upwardly extending parts F², G², and H², from which extend the rearwardly and upwardly projecting tops F³, G³, 100 and H³, respectively. The three parts of each section are V-shaped, having their points in the front and their sides extending rearwardly, as is plainly shown in Fig. 2. Each

plow-section F, G, or H is made hollow, so as to form a steam-space, P, into which steam is admitted from the locomotive D, so as to melt the snow passing on top of the respective sections F, G, and H. The locomotive is provided for this purpose with a pipe, Q, extending in front of the boiler and provided with a valve, Q', for admitting or shutting off the steam from the front end of the said pipe Q. The latter is connected at its front end by a flexible hose, P', with the steam-space P of the middle snow-plow section, G, and the latter is connected by flexible hose P² or P³ with the steam-spaces P of the upper snow-plow, H, and the lower plow-section, F, respectively, as shown in Figs. 1, 2, and 3. The middle part of each plow-section may be provided on its sides with V-shaped ridges G⁴, as shown in Fig. 2.

The operation is as follows: The main frame B, supporting the several plow-sections F, G, and H, is connected by the rods C and C' to the front of the locomotive D, which, when set in motion, pushes the snow-plow into the snow-drift on the railroad-track, whereby the several sections F, G, and H enter the snow in such a manner that the upper section, H, pushes the top layer of the snow-drift to the side of the railroad-track, after which the second section, G, comes in contact with the middle part of the snow-drift and pushes it to the side, after which the lower section, F, takes the remaining part of the snow and pushes it to the side of the track. Thus the several layers of snow in the snow-drift are successively removed, commencing with the top layer, so that the several sections work successively, each removing its respective layer of snow. Part of the snow passing from the several sections is melted by the steam in the steam-spaces. The steam heats the plow-sections, and hence causes the latter to enter easily into hard-packed snow. If the snow-drift is not very high, the lower and middle sections, F and G, respectively, come into use. When the snow-drift is very high, the upper section, H, will also act on the snow, as above described. The several sections can be raised and lowered by actuating the windlass O, so as to wind the chains L on the drum O' or unwind them from the same. When the chains L are unwound from the drum O', the sections H and G swing downward and forward on the stays I and J. This is done in case the snow-drift is not high and the operator desires to bring the three sections into activity.

It will be seen that the sections F, G, and H enter the snow-drift very easily, as the respective flanges F', G', and H' are long and sharp in front, so that the snow easily passes up onto the middle parts, F², G², and H², which deliver the snow to the sides of the railroad-track. Part of the snow which passes over the middle parts, F², G², and H², and on the tops, F³, G³, and H³, is also delivered by the same to the sides of the track, on account of extending upward and rearward and to the

sides of the track. The lower section, F, extends but a short distance beyond the sides of the track-trails, as shown in Fig. 3; but the next section is somewhat wider, and the top section, H, is still wider, as is plainly illustrated in the drawings. The several parts of the plow can be easily taken apart and disconnected from the locomotive and carried in the baggage-car if not needed for the purpose indicated.

Having thus fully described my invention, I claim as new and desire to secure by Letters Patent—

1. In a snow-plow, the combination, with a frame mounted to travel on a railroad-track, of section-plows F, G, and H, pivotally held in front of the said frame one above the other and one in front of the other, substantially as shown and described.

2. In a snow-plow, the combination, with a frame mounted to travel on a railroad-track, of the section-plows F, G, and H, held in front of the said frame one above the other and one in front of the other, and arms pivoted on the said frame and pivotally connected with the said section-plows, substantially as shown and described.

3. In a snow-plow, the combination, with a frame mounted to travel on a railroad-track, of the section-plows F, G, and H, held in front of the said frame one above the other and one in front of the other, arms pivoted on the said frame and pivotally connected with the said section-plows, and chains connected with the upper two section-plows, G and H, to raise and lower the same, substantially as shown and described.

4. In a snow-plow, the combination, with a frame mounted to travel on a railroad-track, of the section-plows F, G, and H, held in front of the said frame one above the other and one in front of the other, arms pivoted on the said frame and pivotally connected with the said section-plows, chains connected with the upper two section-plows, G and H, to raise and lower the same, and a windlass held on the said frame and adapted to wind up the said chains, substantially as shown and described.

5. In a snow-plow, the combination, with a frame mounted to travel on a railroad-track, of the section-plows F, G, and H, held in front of the said frame one above the other and one in front of the other, each of the said section-plows being made hollow to form a steam-space, a steam-pipe connected with one of the sections, and pipes connecting the said section with the other sections, substantially as shown and described.

6. In a snow-plow, the combination, with a frame mounted to travel on the railroad-track, of the section-plows F, G, and H, held in front of the said frame one above the other and one in front of the other, each of the said section-plows being made hollow to form a steam-space, a steam-pipe connected with the middle plow-section, G, and flexible pipes connecting the several steam-spaces with each

other, substantially as shown and described.

7. In a snow-plow, the combination, with a frame mounted to travel on the railroad-track, of the section-plows F, G, and H, each provided with a lower flange continuing into the rearwardly and upwardly extending middle part, which terminates in the rearwardly and upwardly extending top, substantially as shown and described.
10. 8. In a snow-plow, the combination, with the frame B, mounted to travel on a railroad-track, of the hollow section-plows F, G, and H, held in front of the said frame one above the other and one in front of the other, the stays I and J, connected with the said section-plows, and the rods K and K', pivotally connected with the said frame and with the upper two section-plows, G and H, substantially as shown and described.
20. 9. In a snow-plow, the combination, with the frame B, mounted to travel on a railroad-track, of the hollow section-plows F, G, and H, held in front of the said frame one above the other and one in front of the other, the stays I and J, connected with the said section-plows, the rods K and K', pivotally connected with the said

frame and with the upper two section-plows, G and H, the chains L L', connected with the said upper section-plows, G and H, and a windlass, O, mounted on the said frame B and connected with the said chains, substantially as shown and described.

10. In a snow-plow, the combination, with the frame B, mounted to travel on a railroad-track, of the hollow section-plows F, G, and H, held in front of the said frame one above the other and one in front of the other, the stays I and J, connected with the said section-plows, the rods K and K', pivotally connected with the said frame and with the upper two section-plows, G and H, the chains L L', connected with the upper section-plows, G and H, the windlass O, mounted on the said frame B and connected with the said chains, and the frame N, held vertically adjustable on the said frame B and provided with pulleys over which the said chains pass.
